UNITED STATES PATENT OFFICE.

FRANK H. LA PIERRE, OF EAST ORANGE, NEW JERSEY.

DESIGN FOR A BACK FOR BRUSHES OR SIMILAR ARTICLES.

SPECIFICATION forming part of Design No. 31,735, dated October 31, 1899.

Application filed September 27, 1899. Serial No. 731,869. Term of patent 7 years.

To all whom it may concern:

Be it known that I, FRANK H. LA PIERRE, a citizen of the United States, residing at East Orange, in the county of Essex and State of New Jersey, have invented and produced a new and original Design for Backs for Brushes or Similar Articles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan view of a brush-back, showing my new design; and Fig. 2 is a sectional view taken on line *x* of Fig. 1.

As shown in the drawings, the leading feature of my design consists in a back for brushes, mirrors, or similar articles having a raised rib extending around the edges, groups of floral ornaments disposed at opposite ends of the back, and lines of beading ex-

tending along the crest of the raised rib between the floral groups.

In the drawings, *a* indicates the handle, and *b* the body portion of a brush-back of my new design. A raised rib *c* extends around the back near the edge and incloses a central open field *e*, convexly rounded outward. At the opposite ends of the back are arranged groups *f g* of floral ornaments, which lie partly upon the rib *c* and partly in the open field *e*, and upon the convexly-rounded crest of the rib *c* lines of beading *d* extend between the groups of floral ornaments.

What I claim as new is—

The design for a back for brushes or similar articles, as herein shown and described.

In testimony that I claim the foregoing I have hereunto set my hand this 12th day of September, 1899.

FRANK H. LA PIERRE.
